UNITED STATES PATENT OFFICE.

OLIE T. NELSON, OF WAUKEGAN, ILLINOIS.

BOILER.

Application filed November 19, 1920. Serial No. 425,076.

To all whom it may concern:

Be it known that I, OLLIE T. NELSON, a citizen of the United States, and a resident of Waukegan, in the county of Lake and State of Illinois, have invented certain new and useful Improvements in Boilers, of which the following is a full, clear, and exact description.

The invention relates to the manufacture of steel or plate water legs or supporting walls for boilers. In the manufacture of steel or plate boilers it has been customary to form water-legs in double wall structures and to space the inner and outer walls apart by rivets or similar devices. One object of the invention is to provide an improved double-wall structure in which the use is avoided of rivets and like spacing devices.

Another object of the invention is to provide an improved method of constructing double-wall structures for boilers.

The invention consists in the several novel features hereinafter set forth and more particularly defined by claims at the conclusion hereof.

In the drawings: Fig. 1 is a side elevation of a boiler embodying the invention, a portion being broken away and shown in section. Fig. 2 is a horizontal section through the supporting structure taken on line 2—2 of Fig. 1. Fig. 3 is a detail perspective of a portion of said structure. Fig. 4 is a vertical section on line 4—4 of Fig. 2. Fig. 5 is a section taken on line 5—5 of Fig. 4.

The invention is illustrated as applied to a heater comprising a horizontal boiler 7 containing smoke flues connected to a smoke outlet 8 and a water chamber of usual construction and as well understood in the art. The boiler 7 rests upon a structure which forms a support therefor and, in effect, water legs around the fire-box and below the boiler. This structure may rest upon any suitable bed and contains the usual bridge-wall and grate, as well understood in the art. This supporting structure is built up of a plate 9 which is shaped to form a continuous outer wall 10, a bottom 11, the lower portion 12 of the inner wall, the top 13 and the upper portion 14 of the inner wall of the structure, all integral, with a gap between the inner-wall portions 12 and 14. This gap is closed by a series of plates which are secured together to complete the inner wall between said upper and lower portions and are flanged outwardly and secured to the outer wall

to provide spacing means and passages between the inner and outer walls. In the manufacture of these structures, the outer plate with bottom 11, top 13 and upper and lower inner walls 12 and 14 is first formed. Next, a plate 15 with marginal out-turned flanges 16 is secured to the outer wall by welding the edges of both of the flanges to the outer wall. This plate 15 provides surfaces to which contiguous angular plates 17 may be secured. Plates 17, each comprising a portion 17' adapted to form a portion of the inner wall and a flange 18 extending to the outer wall, are secured to the sides 70 of plate 15 and to the outer wall by welding all contiguous surfaces together. Additional plates 17 are then serially secured to one another and to the plate 9 until the entire inner wall has been completed, with the usual openings therein where desired. Usually, a plate 15 is secured to each side of the structure and plates 17 are added until the structure has been completed. The upper and lower meeting edges of the plates 15, 80 17 and portions 12 and 14 of plate 9 are bevelled and welded to one another as at 20. The edges of the flanges of plates 15 and 17 are bevelled and welded to the wall 10, as shown at 21.

When the double walls are formed in this manner, the angular flanges of the plates, which are welded to the inner face of the outer wall, serve as spacing and securing means between the inner and outer walls 90 which render the structure efficient in withstanding the stresses to which they are subjected in practice and also divide the space into vertical water-passages.

The invention exemplifies a boiler wall 95 which is formed of plates welded together and in which flanges serve to space and secure the inner and outer walls together.

The invention also exemplifies a method of making double walled or plate boilers in 100 which rivets and the like are dispensed with.

The invention is not to be understood as restricted to the details set forth since these may be modified within the scope of the appended claims without departing from the 105 spirit and scope of the invention.

Having thus described the invention, what I claim as new and desire to secure by Letters Patent, is:

1. A double walled boiler structure comprising a continuous plate forming one of the walls and extended to form a portion of

the other wall, and a series of angular plates secured to the extended portion of the said one wall and arranged to form another portion of said other wall, each angular plate having one of its edges abutting against and secured to the other wall and another edge abutting against and secured to the corner of an adjoining angular plate.

2. A double wall boiler structure comprising a continuous plate forming one of the walls and extended to form upper and lower portions of the other wall, and a series of plates secured to one another and to the continuous plate and extending between said

upper and lower portions to complete said 15 other wall and having flanges secured to the continuous plate.

3. A double-wall boiler structure comprising a continuous plate forming one of the walls and extended to form upper and lower 20 portions of the other wall, and a series of plates welded to one another and to the continuous plate and extending between said upper and lower portions and having flanges welded to the inner face of the continuous 25 plate.

OLLIE T. NELSON.
